UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

WORK WEB FOR TYPEWRITERS.

Application filed April 25, 1919. Serial No. 292,568.

To all whom it may concern:

Be it known that I, JESSE A. B. SMITH, a citizen of the United States, residing in Stamford, in the county of Fairfield and 5 State of Connecticut, have invented certain new and useful Improvements in Work Webs for Typewriters, of which the following is a specification.

This invention relates to work-sheets for 10 manifolding, and is herein disclosed as applied to work-sheets in the form of separate webs, especially adapted to be used in the type of billing machine known as the Underwood fan-fold typewriting machine, one 15 form of which is disclosed in the patent to Wernery and Smith, No. 1,132,055, of March 16, 1915.

One difficulty which hitherto has been fundamental in attempting to use a plurality of superposed webs, or a pack of webs, 20 for the separate copies to be made in typewriting machines, has been the fact that the outside webs tend to feed faster than the inside webs during the turning of the platen, 25 so that the resulting creeping of the outside webs causes lines or forms upon the various webs to get out of alignment with each other.

According to the present invention, the webs may be entirely separate from each 30 other, and adapted to be passed separately around the usual typewriter platen. To enable them to be kept in alignment, they may be provided with weakened transverse lines, along which the webs tend to fold, so that if 35 the webs, when slightly out of alignment, are lifted up at a fold by a finger or device placed beneath the lower web, the upper webs will slip back into alignment, being free to slip upon each other. Where the 40 webs comprise printed or other forms, which include a transverse line, the line of weakness advantageously comes along such aforesaid line, thus avoiding any marring of the uniform appearance of the smooth web. It 45 will be evident that the essential requirement for the fold-lines is that the webs shall be more flexible therealong than in other parts and that this result may be obtained most conveniently by weakening the webs along 50 such lines.

Other features and advantages will hereinafter appear.

In the accompanying drawings,

Figure 1 is a perspective face view of a

group of webs embodying the present invention. 55

Figure 2 is a perspective view of the webs folded one way.

Figure 3 is a diagrammatic perspective view of a fragment of a fan-fold typewriting 60 machine carriage, showing the webs passed around it and in the act of being severed.

Figure 4 is a sectional side view of some of the parts seen in Figure 3, showing one way 65 of aligning the webs while in the typewriting machine.

As herein illustrated, the outside web 1 is used in combination with rear webs 2, 3 and 4, each web having printed or marked thereon a transverse line 5, which may be part of 70 a form printed thereon. The webs 1, 2, 3 and 4, in coming to the typewriting machine, are drawn from one or more rolls, or other holding devices, and come over the rear end of a frame 6, which travels with 75 the typewriter carriage 7, and are passed around the platen 8, coming up in front thereof behind the usual severing knife 9. The webs are customarily aligned against the usual adjustable end-gage 10, mounted 80 upon the usual extension 11 of the front paper-table 12. To effect this, the platen 8 is journaled in the usual swing-frame 13, so that it may be swung up to the position seen in Figure 4, in which position the webs 1, 2, 85 3 and 4 may be drawn forward freely over the frame 6 and gaged against the gage 10. After the webs have been gaged in this way, the typist usually pushes rearwardly a carbon-paper-carriage, which travels upon the 90 frame 6, so as to carry rearwardly the carbons 14; the adjustments, in using the present invention, being advantageously such that the carbons are carried behind and clear of the weakened line 15, which may be 95 formed as a part-perforated line upon each of the webs 1, 2, 3 and 4. The line 15 advantageously coincides with one of the lines 5.

When the webs have been gaged against the end-gage 10 and the carbon-paper-carriage has been pushed rearwardly to the position seen in Figure 4, the typist is usually holding the webs against the end-gage 10 by means of the thumb of the right hand, and has pushed the carbon-paper-carriage rearwardly with the left hand, thus leaving the left hand adjacent the platen. The typist then may relieve the pressure of the thumb 105

upon the webs near the gage 10, and while supporting the webs loosely near this point, may lift the under web 1 with a finger of the left hand at the line 15, which preferably is arranged to fall a little behind the swing-frame 13. This lifting of the webs at the point of folding causes them to slip into alignment with each other, since they are free from each other.

- 10 The typist may then align the webs against the end-gage 10 and swing the platen 8 back to the Figure 3 position as usual, so that the platen bears against the usual feed-rolls 16 and the webs come down along the usual paper-table 17. When in this position, the webs may be easily severed by drawing them against the edge of the knife 9. Since the fold line 15 may be fairly close to the platen 8 in its upper position, it may advantageously 15 form the upper line of a bill-head, for example, which serves to divide the heading of the bill from the items.

Variations may be resorted to within the scope of the invention, and portions of the 20 improvements may be used without others.

Having thus described my invention, I claim:

1. A printed form device to receive type-writing consisting of a multiplicity of separate plies which creep one relatively to another when passing around the cylindrical platen of a typewriting machine so that superposed forms on the different plies are moved out of register, said device having at 25 intervals re-registering means, consisting of cross fold-lines of greater flexibility including all the plies at each group of cross fold-lines, so that the disarrangement of the register of the plies may be corrected by releas-

ing the plies from the platen and tucking them together in the fold nearest the platen, and then restoring them to their extended condition, thereby restoring the register of the plies with one another.

2. A printed form device to receive type-writing consisting of a multiplicity of separate plies which creep one relatively to another when passing in extended form around the cylindrical platen of a typewriting machine so that superposed forms normally in 45 register are moved out of register, said device having at intervals re-registering means comprising flexible fold-lines so that, by releasing the plies from the platen and lifting them at the fold-lines, folds will be formed 50 by bending the plies and these folds will slip together and again the forms will be brought into register.

3. In combination, a plurality of superposed webs arranged to have identical data 60 printed on them in corresponding positions on superposed forms by a typewriting machine, said webs being provided with re-registering means including flexible fold lines extending across said webs and spaced 65 at suitable distances, so that, when the webs have been advanced a plurality of line-spaces by rotation of the platen and released therefrom, the resultant creeping may be taken up by bending the webs along the fold lines, 70 the resulting folds tending to move into register with each other to re-adjust the forms on said webs with respect to each other.

JESSE A. B. SMITH.
